ALBERT B. CLISSON, OF SYRACUSE, NEW YORK, ASSIGNOR, BY MESNE ASSIGNMENTS, TO THE PROSPERITY COMPANY, INC., OF SYRACUSE, NEW YORK, A CORPORATION OF NEW YORK.

PRESSING MACHINE MECHANISM.

Application filed August 7, 1924. Serial No. 730,760.

This invention relates to garment and laundry pressing machines and has for its object a particularly simple and efficient mechanism for opening and closing the machine entirely by power, which mechanism is so constructed that the movable element or press head has a preliminary closing movement before the power can be effectively applied and is also so constructed that if the movable element or head is prevented by obstructions from completing its preliminary closing movement, the power will not be effectively applied, and further has for its object a particularly simple and efficient mechanism for controlling the intermittent actuation of a drive shaft from a constantly running motor.

The invention consists in the novel features and in the combinations and constructions hereinafter set forth and claimed and described.

In describing this invention reference is had to the accompanying drawings in which like characters designate corresponding parts in all the views.

Figure 1 is a side elevation of a machine embodying my invention, the same being shown as in closed position.

Figure 2 is an enlarged sectional view of the clutch means for connecting and disconnecting the constantly running motor shaft to the intermittently rotatable drive shaft of the machine and the controlling means of said clutch.

Figure 3 is a sectional view on the plane of line 3-3, Fig. 2.

Figures 4 and 5 are sectional views respectively of the cam and closure for controlling the operation of the clutch.

Figure 6 is a transverse sectional view taken on line 6-6, Figure 2 showing the connections for effecting the relative movement of the cam and closure shown in Figures 2, 4 and 5.

Figures 7 and 8 are detail views of another form of closure means.

Figure 9 is a detached elevation of a third form of closure means.

Figure 10 is a detail view of a fourth form of closure means.

Figures 11 and 12 are detail views of the cam and closure shown in Figure 10.

This pressing machine comprises cooperating pressing elements one movable toward

and from the other, means for actuating the movable element comprising a power member, connections between the power member and the movable element and normally arranged out of motion transmitting relation to the power member and movable into effective relation by a preliminary closing movement of the movable element, an intermittently movable drive shaft having an eccentric means coacting with the power member, this drive shaft making a plurality of half revolutions during each intermittent operation, one intermittent operation acting to effect the preliminary closing movement of the movable element and hence bring the motion transmitting connections into effective relation, and to effectively actuate the power member after said connections have been brought into effective relation and to release the pressure and open the press head during the next intermittent rotation of the shaft, connections operated by the shaft to permit the preliminary closing movement and means for effecting and controlling the intermittent rotation of the shaft.

The machine here shown is of the conventional type of garment and laundry pressing machine including a lower pressing element or buck 1, an upper pressing element or head 2 movable toward the buck, the buck being mounted upon a main frame including a table 4 suitably supported by legs or pedestals 5, 6. The head 2 is carried by the forward arm of a vertically movable yoke or lever 7 pivoted at 8 between its ends to an upright 9 forming an extension of the rear leg 6 of the frame.

10 is a vertically movable power member or lever pivoted at 11 to the frame near the base thereof and having an arm 13 extending to the rear of the pivot. The connections between this power lever 10 and the movable element 2, in addition to the yoke or lever 7 includes toggle links 14 and 15 pivoted together at 16 and pivoted respectively at 17 to the rear arm of the lever 7 and to the frame, the link 15 for convenience being mounted on the same pivot 11 that the power lever 10 is mounted on. The connections further include a thrust link 18 pivoted at 19 to the rear arm of the power lever 10 and normally extending upwardly in position to coact with an extension 20 of the

link 14 when the toggle has been partly closed by the preliminary closing of the press.

This link 18 is supported in its initial position by a rod 21 pivoted to the frame and extending through the link 18 and a nut 23 threading on the end of the rod against the rear face 18. A spring is usually interposed between the link and the frame to thrust it against the nut. By turning the nut 23, the position of the link 18 can be varied, and hence the position at which the toggle comes into effective relation thereto varied to suit conditions. These conditions depend upon the thickness of the work to be operated on, it being intended that the head 2 will be preliminarily moved so close to the work on the buck 1 before the toggle comes into effective relation to the link 18, that there is a space so small between the head 2 and the work on the buck 1 that the operator cannot have his hands or fingers between the pressing elements when the power is applied, and if he does have his hands or fingers on the lower buck, the head 2 cannot be closed preliminarily far enough to bring the toggle into effective motion transmitting relation with the thrust link 18.

The pressure is adjusted without affecting the adjustment of the link 18 or the position of the head 2 at the end of the preliminary closing movement of the head 2 by means for adjusting the link 14 endwise without varying the length thereof, that is without varying the distance between the pivots 16 and 17. As here shown, in order to affect this adjustment the link comprises two sections, one slideable in the other, one section including a sliding block 24 movable in the bore 25 in the main section of the link 14, a rod 26 threading through the slide and also threading into a bearing 27 mounted on the pivot 17, the threads of the rod being in the same direction, that is both are right hand threads, the lower end of the rod thrusting against an abutment 28 in the bore 25. Usually this abutment is supported by a stiff spring 29 and a lighter spring is inserted between the abutment and the slide. The rod is turned by means of a wheel 30 slidably keyed thereto. By turning the wheel the rod is caused to project more or less below the slide or block 24 and hence the distance between the end of the rod and the abutment 28 varied.

When the pressure is being applied, the rod bottoms on the abutment. Before the rod bottoms on the abutment the pressure applied is dependent upon the strength of the lighter spring. The adjustment just described of the link 18, and the adjustment of the toggle relative to the thrust link, that is, the adjustment of the gap between the head 2 and buck 1 at the end of the preliminary closing movement, and the adjustment

of the pressure, form no part of this invention.

The head 2 and forward arm of the lever 7 are heavier than the parts carried by the rear arm of the lever 7, so that the head 2 tends to close by gravity, and, in order to more nearly counterbalance the head 2, a weight 31 is connected to the rear arm of the yoke lever 7, this weight being preferably carried in front of the plane of the axis 8 of the lever 7 and being mounted on a downwardly and rearwardly extending arm 31a pivoted at its rear and at 32 and connected to the rear arm of the lever 7 by a link 33.

The preliminary movement of the press head 2 to bring the toggle and the thrust link 18 into effective motion transmitting relation and the actuation of the power lever 10, is effected by an intermittently rotatable shaft 34 which makes more than a rotation during each intermittent movement and during the first part of each intermittent movement effects or permits the preliminary closing of the press head 2 and during the last part effectively actuates the power lever 10. During the first part of each rotation while the press head is preliminarily closing and the toggle links 14 and 15 are being brought into effective motion transmitting relation with the thrust link 18, the power lever 10 and the thrust link merely idle.

In the illustrated embodiment of my invention, the shaft 34 during each intermittent operation makes one and one half revolutions or three half revolutions and the shaft 34 has an eccentric means as a crank pin 35 with a roller 36 thereon coacting with the front arm of the power lever 10.

During the first and second half revolutions, the power lever 10 is merely idled but during the third half revolution the press having been preliminarily closed and the toggle and link 18 brought into effective relation, the power lever transmits motion through the link 18 to the toggle and straightens the toggle toward the dead center line of the toggle, and thus applies power to the press head.

In the event, the operator for any reason places his hands between the press head 2 and buck 1 to straighten out wrinkles etc., during the preliminary closing movement, the head 2 when striking his hand will prevent the head from closing to such a point that the toggle comes into effective position with thrust link 18 and hence the power will not be applied.

The connections for effecting or permitting the preliminary closing movement of the head 2 are operated by the shaft 34 and comprises a second shaft 38 arranged parallel to the shaft 34, a gear 39 on the shaft 34, a second gear 40 mounted on the shaft 38 and meshing with the gear 39; a crank 41 on the shaft 38 and a link 42 connecting the

shaft and a part movable with the press head 2, the link being connected to one of the parts it connects by a lost motion, or pin and slot connection. As the shaft 34 makes a 5 revolution and a half during each intermittent operation, the gearing 39 and 40 is a reduction gearing, the ratio of which is 1 to 3 so that the gear 40 and crank 41 make a half revolution to each intermittent operation, or each one and a half revolutions of the shaft 34. As here illustrated, the link 42 is connected to the weighted arm 31^a by a pin and slot connection 43. Thus when the press is open the crank 41 and link 42 are on 10 the opposite side of the axis of the shaft 38 from that shown in Figure 1 and the weight 31 is depressed and the pin of the pin and slot connection is at the upper end of the slot 43 in the link 42. During the first half 15 revolution of the shaft 34, in the closing movement of the press, the crank 41 tends to move the end wall of the slot up away from the pin, permitting the head to drop half way to its closed position by gravity, 20 the crank making one sixth of a revolution. During the second half revolution of the shaft 34, the crank makes another one sixth revolution permitting the head to move to its preliminary closed position and the toggle 25 to come into effective engagement with the thrust link 18.

During the third and last half revolution, the power is applied to the preliminary closed press head through the link 18, the 30 parts coming into the position shown in Figure 1, so that the power is applied by the cam or roller 36. During the first two half revolutions, the lever 10 and thrust link 18 merely idle as the link 18 is not in effective 35 engagement with the toggle link 14 or the extension 20 thereof. A spring 44 causes the power lever 10 to follow the cam.

To open the press the shaft is again actuated and makes a movement consisting of 40 three half revolutions from the position shown in Figure 1. During the first half revolution, the crank 41 makes one-sixth of a turn to the right from its position shown in Figure 1, moving the weight 31 down far enough to release the pressure on the 45 head 2, the cam in so doing relieving the pressure on the power lever 10. This movement causes the toggle to move out of effective relation with the thrust link 18. The 50 second half revolution of the shaft 34 moves the press head to half way open position and the third one half revolution completely opens the press head 2. During the second and third half revolutions of this intermittent shaft 34, the power lever 10 merely 55 idles.

The shaft 34 is journaled in bearings in a suitable housing 45 and also the shaft 38 is journaled in bearings in a portion 46 of said 60 housing.

The shaft 34 is intermittently actuated from a constantly running motor 47 suitably supported on the main frame of the machine and is connected and disconnected from the motor by a periodic clutch of any suitable 70 construction. As here illustrated, the shaft 34 is driven by a worm 48 mounted on an extension of the armature shaft of the motor and meshing with the worm wheel 49 rotatable about the shaft 34 and mounted concentric therewith and a periodic clutch for connecting the wheel 49 and the shaft 34. As here illustrated, this periodic clutch comprises a shiftable section 50, mounted on the shaft 34 to rotate therewith and slide axially thereof, and clutch pins 51 shiftable by the section 50 into and out of openings 51^a in the web of the wheel 49. The clutch pins are guided in suitable openings in a guide disk 53 arranged adjacent to the web of the gear 49 and the motion of the section 50 is yieldingly transmitted to the pins through a pressure ring 52 thrusting against shoulders on the pins and springs 54 between the pressure ring 52 and the shiftable section 50. 80 A main spring 55 tends to throw the section 50 in its "out" position. The section 50 is shifted into its "in" position by shifting lever 56 mounted on a rock shaft 57 journaled in the housing 45, this lever thrusting 85 against the end of the hub of the section 50. 90

The rock shaft 57 is actuated from a rock shaft 58, Figure 1 mounted on the main frame and having a handle 59 on its front end and also having a rock arm 60 coacting with a rock arm 61 on the shaft 57. The operation is such that upon the depression of the handle 59, the lever 56 will be thrust to the left inwardly and shift the clutch section 50 into interlocking engagement with the worm wheel 49. The clutch is held in its "in" position during each intermittent 95 operation of the shaft 34 by means which will be presently described.

The means for holding the clutch section 50 in its "in" position while the shaft 34 is making a plurality of half revolutions, that is, three half revolutions, comprises a cam ring 65 arranged concentric with the shaft 34 and opposed to the clutch section 50, and having diametrically opposite notches 66, and plain faces 67 between the notches, and followers 68 on the section 50 normally arranged in the notches 66 and shiftable by the operation of the shifting lever 56 out of the notches. Upon the initial rotation of the clutch section 50 they are carried onto the plain faces 67 and hence the clutch section 50 held in its "in" position, until the followers 56 again enter the notches 66. In order to hold the followers out of the notches 66 at the ends of the half revolutions, so that the shaft 34 may make a plurality of half revolutions during each intermittent operation, a closure is provided for holding the 100 105 110 115 120 125 130

followers from entering into the notches until the end of each cycle of movement, this means being actuated by the shaft 34.

As shown in Figs. 5 and 6, one form of this closure consists of a ring 68 arranged concentric with the cams 65 and movable about the axis of the ring 65, the ring 68 having notches 69 normally aligned with the notches 66. During the movement of the clutch section 50 and the shaft 34, the ring 68 is rotated to carry the notches 69 out of alignment with the notches 66, so that, the high or plain faces 70 of the ring 68 obstruct the notches 66 to the entrance of the followers until the end of the cycle of movement of the shaft 34. The movement of the ring 68 is such that the followers are prevented from entering the notches 66 at the end of the first and second half revolutions of the shaft 34.

In Figs. 5 and 6, the ring 68 is shown as having a bearing on and rotatable about the ring or cam 65 and as having peripheral gear teeth 71 meshing with a pinion 72 mounted on the shaft 38. As the ratio of gearing between the shafts 34 and 38, that is, between gears 39 and 40 is one to three, the ratio of the gearing between the pinion 72 and cam ring 68 is also one to three, thus the notches 66 and 69 of the rings 65 and 68 come into alignment at the end of every third one-half revolution.

In the modification shown in Fig. 7 the closure comprises a pair of star wheels 73, having shallow notches 74 and diametrically opposite deep notches 75 arranged to come into alignment with the notches of the cam ring 77, corresponding to the cam rings 65. The followers of the shiftable section 50 are normally located in the notches of the ring 77 and the deep notches 75 of the star wheels, and are shifted manually out of such notches by the operation of the shifting lever 56. During the beginning of the first one-half revolution, the followers engage teeth of the star wheels turning such wheels one step and bringing the deep notches out of alignment with the notches of the cam ring 77. During the next one-half revolution the star wheels are likewise turned another step, and during the third one-half revolution the star wheels are turned another step, bringing the deep notches 75 into alignment with the notches of the cam ring 77, so that, at the end of the third one-half revolution the followers will enter the notches of the cam ring 77 and the clutch section 50 will throw to its "out" position. There are two star wheels 73 arranged diametrically opposite each other, as there are two followers on the clutch section 50. Two followers are used merely to balance the clutch section 50.

In the modification shown in Fig. 9, a ring 78 similar to the ring 68 may be used, this being actuated from the shaft 38, by a

link 79 pivoted at 80 at one end to the ring and at its other end mounted on an eccentric pin 81 on a collar 82 rotatable with the shaft 38. In this construction the ring 78 rocks or oscillates as the shaft 38 is making one and one half revolutions and brings the notch 83 therein out of and into alignment with the notch 84 in the cam ring 85, corresponding to the cam ring 65, once during each three half revolutions.

In Figs. 10, 11 and 12, another closure means is shown, and in this construction the outer notched ring 86 is stationary and the inner cam ring 87 rotatable to bring the notches therein into and out of alignment with the notches in the ring 86. As here shown the ring 87 is driven directly from the shaft 34 through a reduction gearing having a ratio of one to three. The gearing consists of a gear 88, mounted on the shaft 34, and meshing with one or more idlers 89 suitably supported by the housing 45 within the ring 87 and meshing with internal teeth 90 on the ring 87.

In all the forms of closure means shown in Figs. 4 to 12, the notches of the closure means are brought into alignment with the notches of the cam ring at the end of each third half revolution of the shaft 34, which in this embodiment of my invention, makes three half revolutions during each intermittent operation or three half revolutions. The press head is preliminarily closed during the two first half revolutions and pressure applied during the third half revolution of the closing operation. The pressure is relieved and the press part way opened during the first two half revolutions and fully opened during the third half revolution of the opening operation.

The construction of the clutch per se forms no part of my present invention, but constitutes the subject matter of another application, and in so far as this invention is concerned any periodic clutch may be used. By clutch construction per se is meant the shiftable section 50, guide link 53, pins 51, pressure ring 52, springs 54 and throw-out springs 55, and also the controlling of such a clutch by any type of ring. The portion of the clutch construction pertinent to the invention and which makes a periodic clutch adaptable to this invention forms part of the subject matter of this invention. That is the construction of parts and their operation shown in Figures 3, 4, 5 and 6.

What I claim is:—

1. In a pressing machine, the combination of cooperating pressing elements, one movable toward and from the other, means for actuating the movable element comprising a power member, connections between the power member and the movable element including parts normally out of effective motion transmitting relation and movable into

- effective relation by a preliminary closing movement of the movable element, an intermittently rotatable shaft having means associated therewith for coacting with the 5 power member to actuate it, and motion transmitting members between said shaft and the movable pressing element to preliminarily close the press and bring the parts into effective motion transmitting relation 10 during the first movement of the shaft, and moving said parts out of effective relation and opening the press during the last rotation of the shaft, means for driving the shaft, and means for controlling the rotation of the 15 shaft by the driving means.
2. In a pressing machine, the combination of cooperating pressing elements, one movable toward and from the other, means for actuating the movable element comprising 20 a power member, connections between the power member and the movable element including parts normally out of effective motion transmitting relation and movable into effective relation by a preliminary closing 25 movement of the movable element, an intermittently rotatable shaft rotatable more than one revolution during each opening movement and during each closing movement of the movable element, the shaft having means 30 associated therewith for coacting with the power member to actuate it while and after said parts are brought into effective motion transmitting relation, and motion transmitting elements between said shaft and the 35 movable pressing element to preliminarily close such element and bring the said parts into effective motion transmitting relation during the first rotative movement of the shaft during the closing operation, and for 40 moving said parts out of effective relation and opening the press during the latter rotations of the shaft during the opening movement of the press, means for driving the shaft, and means for controlling the rotation of the 45 intermittently rotatable shaft.
3. In a pressing machine, the combination of cooperating pressing elements, one movable toward and from the other, means for actuating said element comprising a power 50 member, connections between the power member and the movable element including parts normally out of effective motion transmitting relation with the power member and movable into effective relation by a preliminary 55 closing movement of the movable element, an intermittently rotatable shaft having means associated therewith for coacting with the power member to actuate it, and motion transmitting elements between the 60 shaft and the movable element including a weight arranged to move said element preliminarily toward closed position and bring said parts into effective motion transmitting relation during the first rotative movements 65 of the shaft during the closing operation and for moving said parts out of effective relation and opening the press and lifting the weight during the last rotation of the shaft during the opening movement of the press, means for driving the shaft, and means for 70 controlling the rotation of the intermittently movable shaft.
4. In a pressing machine, the combination of cooperating pressing elements, one movable toward and from the other, means for actuating the movable element comprising a power member, connections between the power member and the movable element including parts normally out of effective motion transmitting relation with the power member and movable into effective relation 75 by the preliminary closing movement of the movable element, an intermittently rotatable shaft having an eccentric thereon coacting with the power member to oscillate it, and motion transmitting elements between the shaft and the movable element to preliminarily close such element and bring the parts into effective motion transmitting relation 80 during the first movement of the eccentric by the shaft, and for moving said parts out of effective relation and opening the press during the last rotations of the shaft and the eccentric during the opening of the 85 press, means for driving the shaft, and means for controlling the rotation of the intermittently rotatable shaft more than one revolution during each opening movement and each closing movement.
5. In a pressing machine, the combination of cooperating pressing elements, one movable toward and from the other, means for actuating the movable element comprising a power member, connections between the power member and the movable element including parts normally out of effective motion transmitting relation with the power member and movable into effective relation by the preliminary closing movement of the movable element, an intermittently rotatable 90 shaft having an eccentric thereon coacting with the power member to oscillate it, and motion transmitting elements between the shaft and the movable element to preliminarily close such element and bring the parts into effective motion transmitting relation 95 during the first movement of the eccentric by the shaft and the moving of said parts out of effective relation and opening the press during the last rotations of the shaft and the eccentric during the opening of the press, means for driving the shaft, and means for controlling the rotation of the intermittently rotatable shaft more than one revolution during each opening movement and each closing movement.
- 100
6. In a pressing machine, the combination of cooperating pressing elements, one movable toward and from the other, means for actuating the movable element comprising a power member, connections between the power member and the movable element including parts normally out of effective motion transmitting relation with the power member and movable into effective relation by the preliminary closing movement of the movable element, an intermittently rotatable 105 shaft having an eccentric thereon coacting with the power member to oscillate it, and motion transmitting elements between the shaft and the movable element to preliminarily close such element and bring the parts into effective motion transmitting relation 110 during the first movement of the eccentric by the shaft and the moving of said parts out of effective relation and opening the press during the last rotations of the shaft and the eccentric during the opening of the press, means for driving the shaft, and means for controlling the rotation of the intermittently rotatable shaft more than one revolution during each opening movement and each closing movement.
- 115
7. In a pressing machine, the combination of cooperating pressing elements, one movable toward and from the other, means for actuating the movable element comprising a power member, connections between the power member and the movable element including parts normally out of effective motion transmitting relation with the power member and movable into effective relation by the preliminary closing movement of the movable element, an intermittently rotatable 120 shaft having an eccentric thereon coacting with the power member to oscillate it, and motion transmitting elements between the shaft and the movable element to preliminarily close such element and bring the parts into effective motion transmitting relation during the first movement of the eccentric by the shaft and the moving of said parts out of effective relation and opening the press during the last rotations of the shaft and the eccentric during the opening of the press, means for driving the shaft, and means for controlling the rotation of the intermittently rotatable shaft more than one revolution during each opening movement and each closing movement.
- 125
8. In a pressing machine, the combination of cooperating pressing elements, one movable toward and from the other, means for actuating the movable element comprising a power member, connections between the power member and the movable element including parts normally out of effective motion transmitting relation with the power member and movable into effective relation by the preliminary closing movement of the movable element, an intermittently rotatable shaft having an eccentric thereon coacting with the power member to oscillate it, and motion transmitting elements between the shaft and the movable element to preliminarily close such element and bring the parts into effective motion transmitting relation during the first movement of the eccentric by the shaft and the moving of said parts out of effective relation and opening the press during the last rotations of the shaft and the eccentric during the opening of the press, means for driving the shaft, and means for controlling the rotation of the intermittently rotatable shaft more than one revolution during each opening movement and each closing movement.
- 130

6. In a pressing machine, the combination of cooperating pressing elements, one movable toward and from the other, means for actuating the movable element comprising a power member, connections between the power member and the movable element including parts normally out of effective motion transmitting relation with the power member and movable into effective relation by the preliminary closing movement of the movable element, an intermittently rotatable shaft having an eccentric thereon coacting with the power member to oscillate it, and motion transmitting elements between the shaft and the movable element to preliminarily close such element and bring the parts into effective motion transmitting relation during the first movement of the eccentric by the shaft and the moving of said parts out of effective relation and opening the press during the last rotations of the shaft and the eccentric during the opening of the press, means for driving the shaft, and means for controlling the rotation of the intermittently rotatable shaft more than one revolution during each opening movement comprising a second shaft, a gear on the drive shaft, a gear of larger diameter on the second shaft and having a crank associated therewith and a link connected to the crank and to a part movable with the movable element by a pin-and-slot connection.
7. In a pressing machine, the combination of cooperating pressing elements, one movable toward and from the other, means for actuating the movable element comprising a power member, connections between the power member and the movable element including parts normally out of effective motion transmitting relation with the power member and movable into effective relation by the preliminary closing movement of the movable element an intermittently rotatable shaft having an eccentric thereon coacting with the power member to oscillate it, and motion transmitting elements between the shaft and the movable element to preliminarily close such element and bring the parts into effective motion transmitting relation during the first movement of the eccentric by the shaft and the moving of said parts out of effective relation and opening the press during the last rotations of the shaft and the eccentric during the opening of the press, means for driving the shaft, and means for controlling the rotation of the intermittently rotatable shaft more than one revolution during each opening movement and each closing movement, said motion transmitting elements between the shaft and the movable element to preliminarily close the press comprising a second shaft, a reduction gearing between the shafts and said controlling means including a part actuated by the second shaft.
8. In testimony whereof, I have hereunto signed my name, at Syracuse, in the county of Onondaga, and in the State of New York, this 28th day of July, 1924.

ALBERT B. CLISSON.
